[57] CLAIM

The ornamental design for a trash can holder, as shown and described.

DESCRIPTION

FIG. 1 is a perspective view of a trash can holder showing a first embodiment of my new design;
FIG. 2 is a side elevational view of the trash can holder of FIG. 1;
FIG. 3 is a top plan view of the trash can holder of FIG. 1;
FIG. 4 is a bottom plan view of the trash can holder of FIG. 1;
FIG. 5 is a perspective view of the trash can holder showing a second embodiment of my new design;
FIG. 6 is a side elevational view of the trash can holder of FIG. 5;
FIG. 7 is a top plan view of the trash can holder of FIG. 5;
FIG. 8 is a bottom plan view of the trash can holder of FIG. 5;
FIG. 9 is a perspective view of the trash can holder showing a third embodiment of my new design;
FIG. 10 is a side elevational view of the trash can holder of FIG. 9;
FIG. 11 is a top plan view of the trash can holder of FIG. 9;
FIG. 12 is a bottom plan view of the trash can holder of FIG. 9;
FIG. 13 is a perspective view of a trash can holder showing a fourth embodiment of my new design;
FIG. 14 is a side elevational view of the trash can holder of FIG. 13;
FIG. 15 is a top plan view of the trash can holder of FIG. 13; and,
FIG. 16 is a bottom plan view of the trash can holder of FIG. 13.
